UNITED STATES PATENT OFFICE.

GEORGE F. SEISER, WILLIAM T. HILL, AND WILLIAM L. NUTTALL, OF PORT ROYAL, ASSIGNORS TO SAID SEISER AND W. J. COGLE AND W. F. BREWER, OF LOUISVILLE, KENTUCKY.

VEHICLE-TONGUE SUPPORT.

SPECIFICATION forming part of Letters Patent No. 392,640, dated November 13, 1888.

Application filed April 27, 1888. Serial No. 272,068. (No model.)

To all whom it may concern:

Be it known that we, GEORGE F. SEISER, WILLIAM T. HILL, and WILLIAM L. NUTTALL, citizens of the United States, residing at Port 5 Royal, in the county of Henry and State of Kentucky, have invented a new and useful Improvement in Thill Elevators and Supports, of which the following is a specification.

Our invention relates to improvements in 10 thill elevators and supports; and it has for its object to provide a simple, cheap, durable, and efficient support which will hold the thills in either the operative or the elevated position, and which will enable the same to be changed 15 from one position to the other without disengaging any locking device; furthermore, to provide means for supporting the thills in the operative position, such that they are allowed a vertical swing to accommodate the movements of the horse, and, furthermore, to provide means which may be employed in connection with any ordinary thill-coupling.

The invention consists in a certain novel construction and combination of devices, fully 25 set forth hereinafter in connection with the accompanying drawings, wherein—

Figure 1 is a side view of a thill provided 30 with the improved support and adjusted in the operative or horizontal position. Fig. 2 is a similar view with the thill raised. Fig. 3 is a front view of the same with the thill in the raised position.

Referring by letter to the drawings, the axle-clip A is arranged over the axle B in the ordinary manner, and is provided on its front side 35 with the forwardly-projecting ears C C, and D represents the thill, which is attached to the thill-iron E, the rear end of which is mounted on a transverse bolt between the said ears C C.

The removable clip-plate F is attached in the usual manner to the clip, and is provided at its 40 front end with the upwardly-curved projection G, the under side of which is provided with a rounded shoulder, H. The upper end of the 45 said projection is rounded, and this, together with the rounded shoulder which is near the upper end of the projection, forms a rounded knob, the function of which will be hereinafter explained.

The curved spring I is attached at its upper 50 end to the under side of the thill-iron by means of the bolt K, which passes through the thill-iron and the clip and clip-plate L and M, which embrace the spring a short distance below the said bolt, and the lower end of the spring is 55 provided with a rounded portion or hook, N, which bears and slides on the rounded under side of the projection G.

When the hook N is below the rounded shoulder on the projection G, the thills are held in 60 their horizontal or operative position, and when the hook is above the same, or bearing on the upper side of the rounded knob, the thills are elevated. When the hook is below the shoulder and a weight is placed on the thill, it 65 is depressed, and the end of the spring slides on the rounded under surface of the projection; but when the weight is removed from the thill the strength of the spring raises the thill to its original or operative position.

We are aware that it is not broadly new to provide the thill-coupling with a curved series of ratchet-teeth and attach a spring to thill to engage the said teeth, whereby the thill may be held at any desired height, and we do not claim 75 this construction. It will be noticed that when the ratchet is used the thills may be raised without manipulating the locking device; but in order to lower the thills the spring must be disengaged from the ratchet. It is to obviate 80 this inconvenience that we provide the rounded shoulder, over which the end of the spring may be moved in either direction without operating it separately. Therefore, to lock the thills in the elevated position simply raise 85 them until the lower end of the spring engages over the rounded knob on the end of the projection, and when about to attach the horse to the vehicle it is simply necessary to place the horse under the thills and draw the latter down 90 over him with one hand.

It will be seen that the improved clip-plate may be substituted for the ordinary clip-plate in any thill-coupling.

Having thus described our invention, we 95 claim—

1. In a thill-support, the combination, with the clip having the thill-iron mounted thereon,

of the clip-plate F, attached to the clip and having a rounded projection, G, provided with a rounded shoulder, H, and a rounded knob above the said shoulder, and the spring I, attached to the under side of the thill-iron, and provided with a rounded or hooked lower end bearing on the projection G, the bolt K, passing through the thill-iron and the end of the spring, and the clip L and plate M, embracing the thill, thill-iron, and the spring, substantially as and for the purpose specified.

IC 2. In a thill elevator and support, the combination, with the clip, the thill-iron mounted thereon, and the thill secured to the thill-iron, of the clip-plate F, attached to the clip and having a rounded projection, G, provided with a rounded shoulder, H, and a rounded knob above the said shoulder, the spring I, attached

to the under side of the thill-iron, and having a rounded or hooked lower end bearing on the projection G, the bolt K, passing through the thill-iron and the end of the spring, and the clip L and plate M, embracing the thill, thill-iron, and the spring, substantially as and for the purpose specified. 20

In testimony that we claim the foregoing as our own we have hereto affixed our signatures in presence of two witnesses.

GEORGE F. SEISER.

WILLIAM T. HILL.

WILLIAM L. NUTTALL.
